UNITED STATES PATENT OFFICE.

CHARLES JENKINS, OF BOSTON, MASSACHUSETTS.

CHECK-VALVE.

SPECIFICATION forming part of Letters Patent No. 293,328, dated February 12, 1884.

Application filed February 17, 1883. (No model.)

To all whom it may concern:

Be it known that I, CHARLES JENKINS, of Boston, in the county of Suffolk and State of Massachusetts, a citizen of the United States, have invented a certain new and useful Improvement in Check-Valves, of which the following is a full, clear, and exact description, reference being had to the accompanying drawings, forming a part of this specification, 10 in explaining its nature, in which—

Figure 1 is a side elevation of my improved valve. Fig. 2 is an end elevation thereof. Fig. 3 is a vertical central section, and Fig. 4 is an end view of the portion A'.

15 The nature of the invention is disclosed by the following description:

A represents the valve-casing, which is cylindrical in form, and has the screw-thread *a* upon its interior, about the opening *a'*, and 20 the screw-thread *a*² about the opening *a*³.

B is the shoulder, which is formed upon the end of the part A', and has the valve-seat *b*, of resilient packing, like the "Jenkins packing," which is held between the screw-binding and protecting-ring *b'* and the shoulder *b*² of the shoulder B. The shoulder B has upon its exterior the screw-thread *b*³, which may be either right or left hand, and which screws into the thread *a* of the valve-casing A, and 30 the portion A' also has the right or left screw-thread *b*⁴, whereby the valve is fastened or secured to the steam-pipe. By making the thread *a* a left-hand thread and the thread *b*³ a right-hand thread this portion of the valve 35 may be used as a coupling-nut in uniting the remainder of the valve-casing to the connecting-pipe.

The valve C consists of a disk, *c*, having a projecting wall, lip, or extension, *c'* which 40 is narrower than the packing-seat *b*, and which is adapted to shut thereon, and it also has an arm, *c*², which extends into the recess *a*⁴, formed upon the side of the valve-casing A in casting, in which recess it is pivoted by 45 means of the screw or pin *c*³, which extends across the recess from one side, as represented. The recess must be so arranged in relation to the valve-seat as to give the valve sufficient play to seat upon the packing. In order to 50 use this packing in the seat it is essential that

the shoulder be made as represented, and attached to the casing A, as shown, and the construction also enables the interior of the valve-chamber to be easily reached, and lessens the cost of manufacture.

Having thus fully described my invention, I claim and desire to secure by Letters Patent of the United States—

1. In a check-valve, the combination of the casing A, having the valve C hinged thereto, 60 as described, with the removable section A', having the shoulder B integral therewith, and a valve-seat, *b*, of resilient or elastic packing, supported by said shoulder B, all substantially as and for the purposes described. 65

2. The combination, in a check-valve, of the section A', having the shoulder B, provided with the seat *b*, of Jenkins or other resilient packing, screwed to the shell or casing A, with the said casing A, having a recess, *a*⁴, formed in casting it, and a valve, C, having an arm, *c*², extending into said recess, and fastened therein by a screw-pivot, *c*³, all substantially as and for the purposes described. 75

3. In a check-valve, the combination of the valve-casing A, supporting the hinged valve C, and having the screw-thread *a'*, with the section A', having the resilient or elastic valve-seat *b*, and the screw-thread *b*³, all substantially 80 as and for the purposes described.

4. In a check-valve, the combination of the casing A, bearing or supporting the hinged valve C, and having the screw-thread *a*, with the section A', having a resilient or elastic 85 valve-seat *b*, the screw-thread *b*³, and the screw-thread *b*⁴, all substantially as and for the purposes described.

5. In a check-valve, the combination of the casing A and the hinged valve C with the section A', having the shoulder B, supporting the resilient or elastic packing *b*, secured thereto by the screw-sleeve *b'*, and also having the screw-thread *b*⁴, all substantially as and for the purposes described. 90

CHARLES JENKINS.
